GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,261,304.

Specification of Letters Patent.

Patented Apr. 2, 1918.

Application filed January 6, 1917. Serial No. 140,919.

To all whom it may concern:

Be it known that I, GEORGE A. SEIB, a citizen of the United States, and resident of Ilion, in the county of Herkimer and State 5 of New York, have invented certain new and useful Improvements in Type-Writing Machines, of which the following is a specification.

My present invention relates to paper controlling devices for typewriting machines, and more especially to what is commonly known as "platen sweep mechanism" for such machines, the general object of the invention being to provide new and improved 10 mechanism of the character specified. By the use of my improvements the paper when first inserted into the machine may be advanced rapidly to variable predetermined extents and arrested in position for writing 15 the first line; also the paper may be advanced rapidly thereafter a considerable distance from one printing line to another, and when the writing on the sheet has been finished the work sheet may be fed quickly out 20 of the machine. In short, all of the usual functions of a platen sweep mechanism may be performed and the distances through which the paper or work sheet may thus be swept or fed by the use of my invention are 25 not restricted to the extent of some prior constructions but may equal practically a distance corresponding to a complete revolution of the platen.

To the above and other ends which will 30 hereinafter appear, my present invention consists in the features of construction, combinations of devices and arrangements of parts hereinafter described and particularly pointed out in the claims.

40 In the accompanying drawings which illustrate the preferred form of my invention applied to a No. 10 Remington front-strike typewriting machine,

Figure 1 is a fragmentary end view of the 45 carriage of said machine showing my invention applied thereto, some parts being sectioned away for the sake of clearness.

Fig. 2 is a fragmentary front elevation, partly in section, of said carriage.

50 Fig. 3 is a transverse sectional view, taken on a plane indicated by the dotted line $\alpha\alpha$ in Fig. 2 and looking in the direction of the arrows at said line.

Fig. 4 is a longitudinal sectional view, taken substantially on the plane indicated by 55 the dotted line $\gamma\gamma$ in Fig. 1 and looking in the direction of the arrows at said line.

Fig. 5 is a fragmentary view corresponding to Fig. 1 but showing the parts as they appear after the platen sweep mechanism 60 has been operated and prior to its return to normal position.

Fig. 6 is a detail view partly in section.

Fig. 7 is a perspective detail view showing parts separated or spread. 65

Figs. 8 and 9 are operating views.

Referring first to Figs. 1, 2 and 4, the top plate 1 of the main frame of the machine supports pairs of upstanding lugs or standards at its front and rear, one of the two 70 rear standards 2 being shown. The standards have fixed to them grooved guide rails, the rear guide rail 3 coöperating through anti-friction balls 4 with the grooved rear bar 5 of a carriage truck. Said truck further comprises end bars 6 which connect the rear bar with a similarly grooved front bar that also coöperates through anti-friction balls with the front trackway, the front bar and trackway with the coöperating balls being omitted however from the drawings. In addition to the truck the carriage of the machine further comprises a platen frame that is mounted on the truck, said frame including end bars 7 that are connected by devices 80 comprising a cross bar 8. Mounted on the carriage is a cylindrical platen 9 provided with platen heads and stub shafts or spindles, the right-hand head 10 and spindle 11 being shown. Surrounding the spindle 11 90 is a hollow shaft 12 that has fixed to its left-hand end a flange 13 provided with a lateral pin 13a that engages in a hole in a ratchet wheel 14 that is normally connected with the platen in the manner that is usual 95 in the No. 10 Remington machine. Coöperative with the ratchet wheel 14 is the usual detent roller 15 and line spacing mechanism of regular construction by which the platen may be turned step-by-step through line 100 space distances. Said mechanism comprises a pawl 16 pivoted at 17 to an arm or carrier 18 that is pivotally mounted concentrically with the platen, the pawl being connected by devices comprising a link 19 with a line 105 spacing handle (not shown). The usual reg-

ulating devices comprising an adjustable stop device 20 that coöperates with the carrier 18 are employed to adjust the step-by-step line spacing devices for turning the platen through one, two or three units of line space distance each time the line spacing handle is operated. Coöperative with the platen to feed the paper when the platen is thus turned are devices comprising feed rollers 21 and 22 at the under side of the platen and pressure rolls 23 at the front upper side of the platen, said rolls being mounted on the usual guides or fingers 24.

The hollow shaft 12 passes through and bears in a sleeve 25 (Fig. 4) which is threaded into the right-hand end bar 7 and extends outward therefrom through an opening in the right-hand end bar 6. The sleeve terminates at the left in a hexagonal head 25^a, the space between the head and the inner face of the end bar 7 providing a bearing for the parts 18 and 20 of the regular line spacing mechanism. The bearing portion is separated from the threaded portion by a shoulder 25^b which abuts against the inner face of the end bar 7, a clamping nut 26 coöperating with the outer face of said end bar to hold the sleeve rigid on said end bar. The outer end of the sleeve 25 is reduced as indicated at 25^c and is rigidly connected with an upstanding arm 27 which is fixed to a hub or bearing portion or lug 28 that is integral with an arm 29 that in turn is fixed by screws 30 to the rear portion of the end bar 7 outside the latter, said arm 29 extending horizontally forward from its support, the hub portion 28 being arranged above the platen and slightly in rear of a vertical plane passing through the platen axle. The arm 27 acts as a tie or brace to hold the bearings 25 and 28 in rigid relationship.

The platen sweep mechanism includes a sweep proper or lever member comprising a bearing or pivot portion 31 and a handle portion 32. The hub 28 is bored out to provide a bearing opening for the pivot 31 which extends therethrough and has secured at its left-hand end a headed screw 31^a which prevents displacement of the lever member 31, 32 lengthwise of its bearing. Concentric with the pivotal axis of the handle 32 there is secured at the right of said axis a screw stop 33. It will be apparent that while this screw stop whose function will be explained hereinafter rotates with the sweep to which it is secured, said stop is, nevertheless, in essential, fixed, its bodily position always remaining the same. The upper end of the handle or sweep 32 is provided with a laterally extending curved finger piece 34, and its lower end portion is broadened out and provided with a series of teeth 35 forming a segmental gear. Of course, the gear 35 may be made separate from the sweep or lever member 31, 32 and

suitably connected thereto but, for convenience of manufacture and compactness, it is preferable to form the gear on the lever member. Normally the handle or lever member is maintained substantially upright by stop devices hereinafter described in coöperation with spring means, said spring means comprising a wire spring 36 which is coiled around the lug 28 and has its inner end anchored at 37 to the arm 29. The outer end of the spring is hooked over a headed screw 37^a on the handle or lever 32. The spring 36 tends constantly to swing the upper arm of the lever 32 rearward about its pivotal axis and to turn the gear 35 forward. This gear constantly meshes with a pinion 38 which is concentric with the platen and bears on the reduced portion 25^c of the sleeve 25. The hub 38^a of the pinion 38 extends rightward along the bearing 25^c and has at its outer end an upstanding arm 40 which as shown in Figs. 3 and 7 is provided with teats 40^a that fit into notches 38^b in the reduced end portion of the hub 38^a, thus fixing the arm 40 rigidly to the pinion 38. Near its free end the arm 40 carries a shouledered screw 41 on which is pivoted a pawl or stop member 42. The bearing portion of this pawl member, as will clearly be seen from Fig. 6, is countersunk to receive a wire spring 43 that is coiled around the shouledered portion of the screw 41 and has one end anchored to the arm 40, the other end of the spring being secured in a hole in the pawl member. The tendency of the spring 43 is constantly to maintain the tooth 42^a of the pawl member 42 engaged with a ratchet wheel 44 which is arranged on the hollow shaft 12 at the right of the arm 40 and has a hub portion 45 that receives a set screw 46 whereby, as will be clearly understood from Fig. 4, the ratchet wheel 44 is secured to the hollow shaft or sleeve 12. It will be apparent that the ratchet wheel 44 is connected rigidly with the platen 9 through the sleeve 12, flange 13, ratchet wheel 14, and the regular Remington connections between said ratchet wheel 14 and the platen, which connections it has not been thought necessary to describe in detail herein. Likewise the turning of the platen by the regular line spacing mechanism will also operate to turn the hollow shaft 12 and ratchet wheel 44, this turning movement being independent of the pinion 38 and the handle 32, assuming the pawl member 42 to be inoperative. With the pawl member operative, however, an actuation of the handle 32 by a forward pull will be transmitted through the segmental gear 35 and pinion 38 to the arm 40 and thence through the pawl member 42 to the ratchet wheel 44, the actuation of the ratchet wheel operating through the described connections to turn the platen. On releasing the handle 32 it will be restored by its

spring, the pawl tooth 42^a clicking over the teeth of the ratchet wheel 44 during this returning movement so that the platen will not be affected thereby, said platen being 5 retained in the position to which it has been advanced, because of the friction exerted by the detent 15 on the ratchet wheel 14 as well as by the coöperation of the feed rollers 21 and 22 and the pressure roller 23 with the 10 surface of the platen.

In order to increase the extent to which the platen may be turned or swept by the operation of the sweeper or lever 32, devices are provided comprising a rotary member or 15 plate 47 which is loosely mounted on the hub 38^a just to the right of the pinion 38. Said member 47 extends outward from its support in a fan-like shape, its outer surface 48 being struck from the platen axis as a center, said surface terminating at its ends, as will best appear from Figs. 3 and 5 in two lugs, hooks or stop portions 49 and 50. These sub-stops or arresting devices are both adapted to coöperate with the screw stop 33 20 which acts as a stationary or final stop or arresting device. During the movements of the member 47 as hereinafter described the curved surface or edge 48 passes back and forth under the shouldered portion of the 25 screw 33, the head of said screw confining the member to a path of movement contiguous to the outer face of the segmental gear 35. Fixed to the member 47 and extending laterally rightward therefrom is a 30 screw stop or pin 51 which also serves as a pivot for a pawl device or member 52. The tail of the pawl has an outwardly bent portion 53 into which is hooked a coiled spring 54, the other end whereof is anchored to a 35 pin 55 on the member 47. The spring 54 tends to maintain the tooth 52^a of the pawl 52 engaged with a set of ratchet teeth 56 that are formed on and comprise part of an 40 adjustable stop member 57 that is loosely 45 mounted on the hub 38^a to the right of the member 47. The stop member 57 further 50 comprises a radially extending stop arm 58 that is provided with a lateral stop pin 59 that is substantially at the same radial 55 distance from the center of rotation as is the traveling screw stop 51. This stop 59 is adapted for coöperation with the outer 60 face of the pawl tooth 42^a while the screw stop 51 is adapted for coöperation with the back of the pawl member 42 at the opposite side of its pivot from the pawl tooth 42^a, and said back portion indicated at 42^b being curved or shaped to coöperate with the screw stop 51 in such a way that when the 65 parts are in normal position, as illustrated in Fig. 1 the effect of the screw stop is to overcome the pawl spring 43 and hold the pawl 42^a out of engagement with the ratchet wheel 44. The ratchet 56 and the spring 70 mounted pawl member 52 provide an ad-

justable connection between the stop member 57 and the member 47 which affords an adjustment between the two stops 51 and 59. Referring to Fig. 3 it will be apparent that by using the stop 59 as a handle the stop 70 member 57 may be turned leftward, separating the stops 51 and 59 to a greater extent than they appear in Fig. 3. After the relation of the stops has been properly adjusted the pawl tooth 52^a, coöperating with 75 the ratchet teeth 56, will maintain the two stops set in adjustable relationship, connecting the stop member 57 with the member 47 so that these two members in effect will rotate back and forth during the operation 80 of the platen sweep mechanism as a single member or unit. It will be clear that the number of different relationships in which the two stops 51 and 59 may be set correspond to the number of teeth in the ratchet 85 wheel 56.

In Fig. 3 the stop devices 51 and 59 are set to give the greatest extent of movement to the platen under the operation of the platen sweep mechanism. By moving the 90 stop 59 down away from the stop 51 and setting it in the turning movement communicated to the platen will be diminished to a greater or less extent. Such a setting is 95 illustrated in Fig. 8. Subsequently in resetting the stop 59 to increase the platen turning movement or throw, the pawl 52 will be swung back against the spring 54 and into contact with the stop pin 60, thus freeing the ratchet 56 from the pawl tooth 52^a 100 and permitting the stop member or carrier 57 to be turned to bring the stop 59 clear to the stop 51. Thereafter, freeing the member 52 will cause the pawl tooth 52^a to re- 105 engage with the ratchet wheel 56, thus interlocking the stop carrier 57 and the member 47 in a new set relationship with respect to the stop pins 59 and 51. These pins 51 and 59 not only act as stops but as a further 110 function of actuating devices as will herein- after appear.

Referring to the operation of the platen sweep mechanism, the parts comprising this mechanism will normally be maintained as in Figs. 1, 2 and 3, leaving the platen free to be 115 turned by the regular line spacing mechanism independently of the platen sweep mechanism. The normal position of the parts of the platen sweep mechanism is determined primarily by the fixed or final stop 120 33 which is engaged by the stop lug or sub-stop 50 under the compulsion of the spring 36. Said spring acts on the lever 32, segmental gear 35, pinion 38 and arm or driven member 40, which through the face or curved 125 portion 42^b of the driven member or traveling stop 42, acting against the pin or back stop 51, transmits pressure to the member 47 of which the sub-stop 50 is a part. Assuming that a new sheet is to be fed 130

4

forward into the machine, or it may be advanced continuously or fed out of the machine, the finger piece 34 is pulled forward by the operator thus turning the lever 32 on its fulcrum, causing the gear 35 to turn the pinion 38 and arm or carrier 40. This arm will be swung or driven toward the rear carrying with it the pawl member 42. As the pawl member separates from the back stop 51 the pawl spring 43 will become effective, forcing the pawl tooth 42^a into engagement with the ratchet wheel 44. After such engagement further turning movement of the arm 40 will be transmitted to the ratchet wheel and through it to the platen as has been described. This turning movement will continue independently of the member 47 until the pawl or driven member 42 has been turned far enough to bring it into contactive engagement with the pin or front traveling stop 59, after which turning movement of the carrier or arm 40 will be transmitted to the member 47, forcing said member to turn ahead until the limit of movement is reached as determined by the engagement of the substop 49 with the fixed final stop 33, at which time the parts will be in the relationship illustrated in Fig. 5. It will be observed that a limited extent of movement of the sweep, approximately a quarter turn, operates to turn the platen through a substantially complete rotation. As a result of this operation of the platen sweep mechanism the platen will be turned continuously through a distance practically equal to a complete revolution. On releasing the finger piece 34 the lever 32 will swing back under the impulse of the restoring spring 36, this movement being transmitted through the gear 35 and pinion 38 to the carrier 40. The return movement may be independent of the member 47 until the pawl member 42 engages with the pin 51 after which said member 47 will be forced to turn ahead of the carrier 40, the movement of the parts continuing until the stop 50 engages with the fixed stop 33. Since the spring 36 is stronger than the spring 43 the final arrest will not take place until the pawl tooth 42^a has been forced out of the ratchet wheel 44, leaving the parts in the position illustrated in Fig. 1.

For the purpose of making as clear as possible an understanding of the operation of my improvements, reference may be had to the operating views, Figs. 8 and 9, in which the cycle of operations may be followed without confusion since the mechanism apart from the stops proper is substantially omitted from these figures. In Figs. 8 and 9 the front or forward stop 59 is set several notches farther forward away from the back stop 51 than in Fig. 1, this altered arrangement being clearly illustrated in Fig. 7. At the beginning of the operations as shown by

full lines in Fig. 8, the arresting device 50 is in contact with the final stop or arresting device 33 and the driven member 42 is in contact with the back stop 51. As the hand sweep is pulled forward, the driven member 42 will separate from the back stop 51 and will turn around the axis of the platen as a center, the plate 47 being adapted to remain quiescent until the inclined face of the tooth 42^a of the driven member is brought into contact with the front stop 59 as shown by dotted lines in Fig. 8. The position of the sweep 32 when this contact takes place is illustrated in dotted lines in said figure. Thereafter, as the sweep 32 is pulled forward from the dotted line position in Fig. 8 to the full line position of Fig. 9, the plate 47 will be forced ahead, turning rearward or toward the right in Fig. 8, the parts being finally arrested by the arresting means 49, 33, as illustrated in Fig. 9. The return movements of the parts to normal position will take place as has heretofore been described.

It will be observed that by my present invention there is provided novel platen sweep mechanism for typewriting machines or the like comprising a hand sweep and devices for controlling the operation of said sweep; that the controlling devices comprise in combination a pair of traveling stops, in the present instance 51 and 59, and a third stop, 42 in the present instance, that travels between said pair of stops; that said pair of traveling stops are relatively adjustable so that the distance that the third stop moves in traveling from one of these to the other may be varied, (for instance, the distance said third stop travels when the parts are set as in Fig. 1 is greater than when the parts are set as in Fig. 3;) that the traveling stop or driven member, in the present instance 42, is rotatable from a rest position, in which it engages with one of the other traveling stops, to a position in which it engages with another of the traveling stops during the operation of the platen sweep mechanism, the rotation being reversed during the return of the platen sweep mechanism, said driven member or traveling stop thus playing between the other two traveling stops; that arresting means for these traveling stops comprise the hooks or sub-stops 49 and 50 and the final stop 33, said final stop being intermediate the sub-stops; and that these hooks are on a movable or oscillating carrier, in the present instance the fan-like plate 47.

Various changes may be made without departing from my invention.

What I claim as new and desire to secure by Letters Patent, is:—

1. In platen sweep mechanism for a typewriting machine or the like, controlling devices comprising in combination, a pair of traveling stops, and a third stop that travels

between said pair of stops, the sweep mechanism being normally disconnected from the platen so that the platen may be turned both backward and forward to any desired extent without affecting the sweep mechanism including the sweep proper or handle.

2. In platen sweep mechanism for a typewriting machine or the like, controlling devices comprising a pair of traveling stops

10 that are relatively adjustable in respect to each other, and a third traveling stop that travels between said pair of stops, the sweep mechanism being normally disconnected from the platen so that the platen may be 15 turned both backward and forward to any desired extent without affecting the sweep mechanism including the sweep proper or handle.

3. In a typewriting machine, the combination with a platen and step-by-step line spacing devices, of other means for turning the platen comprising a hand sweep and devices for controlling the operation of said hand sweep comprising a pair of traveling 25 stops and a third stop that travels between said pair of stops, a limited movement of the hand sweep operating to turn the platen through a substantially complete revolution.

4. In a typewriting machine, the combination with a platen and step-by-step line spacing devices, of means for turning the platen a greater continuous distance than said line spacing devices are capable of turning it, said means comprising a hand sweep 35 and devices for controlling the operation of said hand sweep including a pair of traveling stops and a third stop that travels between said pair of stops, one of said pair of stops being adjustable, a limited movement 40 of the hand sweep operating to turn the platen through a substantially complete revolution.

5. In platen sweep mechanism for a typewriting machine, the combination of a positively driven stop, a handle, means intermediate said stop and said handle whereby said stop is positively driven, a back stop, and a forward stop for said positively driven stop, said forward stop being mounted to 50 travel simultaneously with said positively driven stop for part of its movement and finally acting to arrest said positively driven stop.

6. In platen sweep mechanism for a typewriting machine, the combination of a positively driven stop, a handle, gearing between said stop and said handle, a back stop, a front stop for said positively driven stop that travels part of the way with said positively driven stop, and means for arresting said front stop so that it may in turn finally arrest said driven stop.

7. In platen sweep mechanism for a typewriting machine, the combination of a positively driven stop, a handle, motion-multi-

plying gearing between said stop and said handle whereby said stop is moved through a greater angular distance than said handle, a back stop and a forward stop coöperative with said driven stop, said forward stop being mounted to travel simultaneously with the driven stop, and relatively fixed means for arresting said forward stop so that it may in turn finally arrest said driven stop.

8. In platen sweep mechanism for a typewriting machine, the combination of a back stop and a front stop, said stops being relatively adjustable angularly and both being mounted for limited rotation, a driven member playing between said stops, a handle, 75 and means intermediate said handle and said driven member whereby said member is positively driven when said handle is actuated.

9. In platen sweep mechanism for a typewriting machine, the combination of a back stop and a front stop, said stops being relatively adjustable angularly and both being mounted for limited rotation, a driven member playing between said stops, a handle, 80 means intermediate said driven member and said handle whereby said driven member is positively driven when said handle is actuated, and relatively stationary arresting devices for said front and back stops. 95

10. In platen sweep mechanism for a typewriting machine, the combination of a driven member, a handle, means intermediate said member and said handle whereby said member is moved when said handle is actuated, 100 and two coöperating stops, said stops having at the beginning of the throw or sweep a certain angular relationship relatively to said driven member, this angular relationship increasing as the driven member is 105 moved so that at the end of the throw it is greatest.

11. In a typewriting machine, the combination of a platen, a pair of traveling stops, a third stop normally disconnected 110 from said platen, and means for causing said third stop to travel between said pair of stops, said means comprising a hand sweep and devices controlled by said hand sweep for connecting said third stop with 115 the platen.

12. In a typewriting machine, the combination with a platen and step-by-step line spacing devices therefor, of other means for controlling the platen comprising a hand sweep and devices for limiting the extent of movement of said hand sweep comprising a pair of traveling stops and a third stop that travels between said pair of stops and is normally disconnected from said platen; 120 and pawl and ratchet devices controlled by said hand sweep for connecting the platen with said third stop.

13. In a typewriting machine, the combination of a platen, a hand sweep, a stop 125

- 65
- positively driven by said hand sweep, said stop being normally disconnected from said platen, a back stop for said driven stop, a front stop for said driven stop that travels part of the way therewith, means for arresting said front stop so that it may in turn 5 finally arrest said driven stop, and means for connecting said platen to travel with said driven stop.
- 10 14. In a typewriting machine, the combination of a rotary platen, a driven member co-axial with said platen, disconnectible connecting devices between the driven member and said platen, a hand sweep separate from said member for driving said member and for causing said devices to connect it with said platen, a stop for said driven member, and arresting means, said driven member being rotatable from its rest position toward said stop, which stop advances 15 until finally arrested by said arresting means and thereafter stops said driven member.
- 15 15. In platen sweep mechanism for a typewriting machine or the like, the combination 20 of a positively driven stop, a handle, means intermediate said stop and said handle whereby said stop is positively driven and arresting means for said positively driven stop comprising two sub-stops, one at least 25 of said sub-stops being movable.
- 30 16. In platen sweep mechanism for a typewriting machine or the like, the combination of a positively driven stop, a handle, means intermediate said stop and said handle whereby said stop is positively driven, and arresting means for said positively driven stop comprising two movable sub-stops and a final stop to coöperate therewith at each 35 end of the throw of the platen.
- 40 17. In platen sweep mechanism for a typewriting machine or the like, controlling devices comprising in combination a movable carrier, a sub-stop thereon, a front stop mounted independently of but adjustably 45 connected to said movable carrier, and a final stop to which said sub-stop is adapted.
- 45 18. In platen sweep mechanism for a typewriting machine or the like, controlling devices comprising in combination a movable carrier, a sub-stop thereon, a front stop supported independently of said carrier, pawl and ratchet devices for adjustably connecting said front stop to said carrier, and a final stop to which said sub-stop is 55 adapted.
- 55 19. In platen sweep mechanism for a typewriting machine or the like, controlling devices comprising in combination an oscillatory sector having fixed stops at its ends, a movable stop having pawl and ratchet 60 connections with said sector and a final stop with which said sub-stop is adapted to coöperate.
- 60 20. In platen sweep mechanism for a type- writing machine or the like, controlling de- 65 vices comprising in combination, a gear driven arm, a pawl carried by said arm, a ratchet wheel with which said pawl co- operates, said ratchet wheel being connected with the platen, a movable carrier, a back stop connected therewith, a front stop connected to said carrier, and a final stop for arresting said carrier in both directions of its movement, said pawl coöperating with said back stop and said front stop.
- 75 21. In platen sweep mechanism for a type- writing machine or the like, controlling de- 70 vices comprising in combination a sub-front- stop, a sub-back-stop, a movable carrier for said sub-stops, a final stop intermediate said 75 sub-stops, a gear driven arm, a pawl connected therewith, and a ratchet wheel connected with the platen, said pawl coöperating with said ratchet wheel and with said sub-stops.
- 80 22. In platen sweep mechanism for a type- writing machine or the like, controlling de- 80 vices comprising in combination a driven stop, four traveling stops, and a fixed final stop, said driven stop playing between two 85 of said traveling stops, said fixed stop being arranged between the other two traveling stops.
- 85 23. In platen sweep mechanism for a type- writing machine or the like, controlling de- 90 vices comprising in combination a driven stop and two traveling relatively movable and relatively adjustable front and back stops, said driven stop playing between said 95 front and back stops, a second pair of trav- 100eling stops, and a fixed stop arranged be- 105 tween said second pair.
24. In platen sweep mechanism for a type- writing machine or the like, controlling de- 105 vices comprising in combination a driven stop and two traveling relatively movable and relatively adjustable front and back stops, said driven stop playing between said 110 front and back stops, a movable carrier for said front and back stops, a pair of movable stops spaced apart on said carrier, and a final fixed stop with which said pair of mov- 115 able stops coöperate.
25. In platen sweep mechanism for a type- writing machine or the like, controlling de- 115 vices comprising in combination sub- 120 stops, an oscillating carrier for said sub- stops, back and front stops movable with said carrier during its oscillations, and a fixed stop arranged between said sub-stops.
26. In platen sweep mechanism for a type- writing machine or the like, the combi- 125 nation of a spring returned handle pro- vided with a gear sector, a pinion driven by said sector, a pawl carrying arm movable by said pinion in both strokes of said handle, a stop carrier, and stops on said carrier, said pawl coöperating with said stops.

27. In a typewriting machine, the combination of a rotary platen, a pinion normally disconnected from the platen, a hand operated rack meshing with said pinion, means for connecting the platen with the pinion to cause the pinion to rotate the platen when the rack is operated, and means interposed between said pinion and said hand operated means for increasing the motion of the platen.
28. In a typewriting machine, the combination of a rotary platen, a pinion normally disconnected from the platen, a hand operated rack meshing with said pinion, means for connecting the platen with the pinion to cause the pinion to rotate the platen when the rack is operated, and means interposed between said pinion and said hand operated means for increasing the motion received by the platen, said last recited means comprising a device free to rotate concentrically with the platen and having a motion limited by a stationary stop.
29. In a typewriting machine, the combination of a rotary platen, a pinion normally disconnected from the platen, a hand operated rack meshing with said pinion, means for connecting the platen with the pinion to cause the pinion to rotate the platen when the rack is operated, and means for increasing the motion received by the platen comprising a freely rotatable device controlled in its movements by said connecting means.
30. In a typewriting machine, the combination of a rotary platen, a pinion normally disconnected from the platen, a hand operated rack meshing with said pinion, means for connecting the platen with the pinion to cause the pinion to rotate the platen when the rack is operated, and means interposed between said pinion and said hand operated means for increasing the motion received by the platen, said last recited means comprising a freely rotatable device controlled in its movements by said first recited means, said freely rotatable device being provided with an adjustable means for variably controlling the extent of rotary movement that said freely rotatable device receives from said first recited means.
31. In a typewriting machine, the combination with a platen and step-by-step line spacing devices therefor; of platen sweep mechanism comprising a hand operated gear, a pinion with which said gear constantly meshes, said pinion being concentric with the platen but rotatable independently thereof, a rotary carrier rigid with said pinion, normally ineffective pawl and ratchet devices for connecting said carrier automatically with said platen when the carrier starts to turn, a freely rotatable device operative by said carrier, and fixed stops for limiting the movement of said freely rotatable device.
32. In a typewriting machine, the combination with a platen and step-by-step line spacing mechanism therefor; of platen sweep mechanism comprising a hand operated rotary carrier, separable connections between said carrier and the platen, said connections being normally disconnected and devices for limiting and turning movement of the carrier and thus determine the extent of sweeping movement or throw communicated to the platen, said devices comprising a member rotatable concentrically with said carrier and provided with two sets of stops, one set cooperative with the carrier, and the other cooperative with a fixed stop.
33. In a typewriting machine, the combination with a platen and step-by-step line spacing mechanism therefor; of platen sweep mechanism comprising a hand operated rotary carrier, separable connections between said carrier and the platen, said connections being normally disconnected, and devices for limiting the turning movement of the carrier and thus determine the extent of sweeping movement or throw communicated to the platen, said devices comprising a rotary member operative by said carrier and provided with stops that cooperate with the fixed stop to limit the extent of the platen sweeping movement.
34. In a typewriting machine, the combination with a platen and step-by-step line spacing mechanism therefor; of platen sweep mechanism comprising a hand operated rotary carrier, separable connections between said carrier and the platen, said connections being normally disconnected, and devices for limiting the turning movement of the carrier and thus determine the extent of sweeping movement or throw communicated to the platen, said devices comprising a rotary member operative by said carrier and provided with stops that cooperate with the fixed stop to limit the extent of the platen sweeping movement, and means for varying the extent of movement which said rotary member may receive from said carrier.
35. In a typewriting machine, the combination with a platen and step-by-step line spacing mechanism therefor; of platen sweep mechanism comprising a hand operated rotary carrier, separable connections between said carrier and the platen, said connections being normally disconnected, and devices for limiting the turning movement of the carrier and thus determine the extent of sweeping movement or throw communicated to the platen, said devices comprising a rotary member operative by said carrier and provided with stops that cooperate with the fixed stop to limit the extent of the platen sweeping movement, and means for varying the extent of movement which said rotary member may receive from said carrier.

which said rotary member may receive from
said carrier, said last recited means com-
prising a stop on said member, and a sec-
ond stop adjustable relatively to the first
5 mentioned stop on said member.

Signed at Ilion, in the county of Herk-

mer, and State of New York, this 4th day
of January, A. D. 1917.

GEORGE A. SEIB.
